UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed October 21, 1919. Serial No. 332,265.

To all whom it may concern:

Be it known that I, CHARLES W. KECKLER, a citizen of the United States, residing at Newark, in the county of Essex, State of New Jersey, have invented certain new and useful Improvements in Telephone Systems, of which the following is a full, clear, concise, and exact description.

This invention relates to telephone exchange systems, and more particularly to such systems in which connections between telephone lines terminating at manual and automatic exchanges are established by way of trunk circuits, over which automatic switches are controlled from the manual exchange for effecting connections between the trunk circuits and telephone lines at the automatic exchange.

The object of this invention is the production of an improved system of this character by which the operators at a manual exchange may control over the trunk circuit, the automatic switches provided at the automatic exchange, for establishing connections between the trunk circuits and the telephone lines.

In accordance with the various features of this invention, the transmission of selecting impulses over the trunk circuit from the manual exchange to the automatic exchange is effected by maintaining an impedance element in a bridge across the talking conductors of the trunk circuit short-circuited during the actuation of the impulse sending device, and intermittently interrupting this bridge whereby the automatic switches at the automatic exchange are controlled. A relay provided in the trunk circuit and controlled over the ring conductor of the engaged link and trunk circuits and responding to the actuation of the impulse sending device connecting key, controls the short-circuiting of the impedance element and a relay controlled over the tip talking conductor of the engaged link and trunk circuits by the impulse sending device controls the intermittent interruption of the bridge. Preferably, these relays are associated with the respective talking conductors only during the time that the impulses are being transmitted.

For a more complete understanding of this invention, reference should be made to the following description considered in connection with the accompanying drawing

which illustrates one embodiment of the invention.

There is shown in the drawing a telephone line A terminating at a manual exchange, where it may be connected with the link circuit B in any suitable and well-known manner. The calling end of the link circuit B may be connected with a trunk circuit C extending from the manual to the automatic exchange, at which are provided the usual selector and connector switches, for effecting connection between the trunk circuit and telephone lines, such as D, terminating at the automatic exchange. At the automatic exchange, the trunk circuit is multiplied to jack terminals at a toll switchboard at which is located the link circuit E, by means of which connection may be established with the trunk circuit and signals at the manual exchange controlled therefrom. The apparatus shown to the left of the dotted line 1-1 is located at the manual exchange, while that shown to the right of the dotted line is located at the automatic exchange. The nature of this invention is such that it is believed a clear understanding thereof will be obtained from a description of the operation of systems shown in the drawing, and it will be so described.

The subscriber at the station on telephone line A having initiated a call and the answering end of the link circuit B having been associated therewith in any well-known manner, the operator actuates listening key 5 connecting the operator's telephone set in circuit so that the operator may converse with the calling subscriber to ascertain the number of the line with which connection is desired. Assuming that connection is desired with telephone line D which terminates at the automatic exchange, the operator inserts calling plug 6 of the link circuit B into jack 7 of the trunk circuit C. Relay 8 thereupon operates over a circuit from battery through the winding of supervisory relay 22, lower normal contact of ringing key 23, ring contacts of the plug 6 and the jack 7, the right-hand normal contact of relay 11, and the winding of relay 8 to ground. Relay 8 in operating opens a contact in circuit with ringing response relay 12, and closes its left-hand alternate contact causing the energization of relay 11 over a circuit from battery through resist-

ance 9, lower normal contact of key 10, sleeve contacts of the plug 6 and the jack 7, left-hand winding of relay 11, normal contact of relay 16 and the left-hand alternate 5 contact of relay 8 to ground. Relay 11 in operating disconnects relay 8 from the ring talking conductor of the trunk circuit but before doing so, establishes at its right-hand alternate contact, a holding circuit for relay 8.

The closure of the right-hand contact of relay 8 causes the energization of relay 13 over a circuit from battery through the right-hand contact of relay 8, winding of relay 13, left-hand normal contact of relay 15, tip contacts of the jack 7 and the plug 6, upper normal contact of key 10, and upper normal contact of ringing key 23 to ground. Relay 13 in operating bridges signal-control relay 16 across the talking conductors of the trunk circuit, whereupon signal-control relay 16 and impulse responsive relay 17 operate over a circuit from battery through the left-hand winding of impulse response relay 17, left-hand contact of cutoff relay 34, contact of relay 13, winding of relay 16, right-hand normal contact of relay 15, right-hand contact of cutoff relay 34, and the right-hand winding of impulse response relay 17 to ground. Relay 16, in operating, removes a short circuit from the high resistance right-hand winding of relay 11, and causes the energization of relay 15 over a circuit from battery through the left-hand contact of relay 11, winding of relay 15, alternate contact of relay 16, and the left-hand alternate contact of relay 8 to ground. Relay 15, in operating also establishes a locking circuit for itself from battery through the left-hand contact of relay 11, winding and inner right-hand contact of relay 15 to ground. Relay 15, in operating, disconnects relay 13 from the tip talking conductor of the trunk circuit, and completes the continuity of the ring talking conductor at its outer left-hand contact. A holding circuit for relay 13 is also established, whereby the continuity of the bridge including signal-control relay 16 is maintained. Relay 15, in operating, removes the short-circuit from impedance coil 18, thereby including this impedance coil in series with the winding of relay 16. Condensers 39 and 40 connected in the talking conductors serve to electrically divide the talking conductors into inner and outer sections to prevent battery from the link circuit B from interfering with apparatus at the automatic exchange and to prevent battery from the automatic exchange from interfering with apparatus connected with the inner section of the talking conductors.

The operator, after inserting the plug 6 into the jack 7, may actuate the impulse sending device connecting key 10 to connect

the impulse sending device 24 with the link circuit B and through the link circuit with the trunk circuit C. The opening of the lower normal contact of this key 10 causes the deenergization of relay 11, whereupon relay 15 releases, short-circuiting impedance coil 18 which is bridged across the talking conductors of the trunk circuit. Relay 8 is reconnected with the ring talking conductor and is held energized. Relay 13 is also held energized through the closure of the upper alternate contact of the key 10 and the contact of the impulse sending device 24. Relay 8 is also reconnected with the ring talking conductor by the deenergization of relay 11 and is maintained energized thereover. Relay 13 which is in circuit with the contact of impulse sending device 24 follows the operation of this device and is deenergized and energized upon each opening and closing of the contact thereof. Therefore, during the operation of the sending device for transmitting the proper number of selecting impulses, relay 13 opens and closes a bridge across the talking conductors of the trunk circuit so that impulse responsive relay 17 follows the actuation of the sending device. Impulse response relay 17 controls the usual motor magnets for causing the proper functioning of the selector and connector switches at the automatic exchange. After the transmission of the proper number of impulses, the trunk circuit C is connected with the telephone line D through the automatic switches 25 and 26.

After the impulses have been transmitted, the operator may restore the key 10 to normal position causing the reenergization of relay 11 which disconnects relay 8 from the ring talking conductor but maintains this relay energized. Relay 15 is reenergized upon the operation of relay 11 and locks up in the manner before described. Relay 15, in operating, also reestablishes the continuity of the ring talking conductor of the trunk circuit, removes the short circuit of impedance coil 18, and disconnects the relay 13 from the tip talking conductor of the trunk circuit. Relay 13 is maintained energized through contacts of relays 8 and 15 and being energized, maintains the bridge including the winding of relay 16 and impedance coil 18. This bridge is of high impedance to talking currents and has little, if any, effect thereon. By maintaining the impedance coil 18 short circuited during the transmission of the selecting impulses, the signaling range is increased. By providing a non-inductive shunt 28 for relay 16, inductive disturbances due to the presence of relay 16 in the circuit while the impulses are being transmitted, are prevented.

The subscriber may be signaled in any

usual and well-known manner, and the subsequent removal of the receiver from the switchhook at the station of the telephone line D completes the talking circuit between telephone lines A and D. At the conclusion of the conversation the receivers are restored to their respective switchhooks. The restoration of the receiver to the switchhook at the station of telephone line A causes the 10 operation of the usual disconnect signal at the manual exchange, whereupon the operator may withdraw the plug 6 from the jack 7 so that all apparatus of the link and trunk circuits is restored to normal position.

15 Should the toll operator at the automatic exchange desire to establish connection with a telephone line terminating at the manual exchange, plug 35 of the toll link circuit E is inserted in jack 36 and ringing key 37 is 20 actuated, whereupon, relay 32 and slow-release cutoff relay 34 operate. Relay 32 causes supervisory lamp 33 to be lighted while cutoff relay 34 disconnects impulse response relay 17 from the talking conductors. 25 Cutoff relay 34 is made slow in releasing to prevent reconnection of impulse response relay 17 with the talking conductors due to any momentary withdrawal of the plug 35 from the jack 36. The actuation of ringing 30 key 37 causes the energization of ring-up relay 12 over a circuit from a source of ringing current 38, through the lower alternate contact of the ringing key 37, ring contacts of the plug 35 and the jack 36, condenser 39, 35 normal contact and winding of relay 12 and the normal contact of relay 8 to ground. Relay 12 in operating establishes a locking circuit for itself from battery through its right-hand alternate contact and winding, 40 and the normal contact of relay 8 to ground. Relay 12, in operating, also causes the lamp 41 to be lighted to furnish a signal to the operator at the manual exchange.

The operator at the manual exchange upon 45 observing the lighted condition of the lamp 41, may insert the plug 6 of the link circuit B into the jack 7 of the trunk circuit C. Relay 8 thereupon operates over the circuit hereinbefore traced, and opens the locking circuit of relay 12 which thereupon releases to extinguish the lamp 41. The energization of relay 8 also causes the energization of relays 11 and 13. The energization of relay 13 causes the operation of supervisory 50 relay 43 and signal-control relay 16 over a circuit from battery through the right-hand winding of supervisory relay 43, lower normal contact of ringing key 37, ring contacts of the plug 35 and the jack 36, contact of relay 13, winding of relay 16, right-hand normal contact of relay 15 or the impedance coil 18 (depending upon the condition of relay 15), tip contacts of the jack 36 and the plug 35, the upper normal contact of 55 ringing key 37 and the left-hand winding of relay 43 to ground. Supervisory lamp 33 is thereby extinguished. The operation of relay 16 removes the short circuit of the high resistance right-hand winding of relay 11 to prevent the lighting of the lamp 30. Relay 15 operates then under the control of the energized relays 11 and 13. The lamp 30 and resistance 31 are connected in parallel with the resistance 9, both of which are in circuit with the two windings of relay 11, 70 but the right-hand winding of relay 11 is of such high resistance that the lamp will not be lighted. The operator at the manual exchange may actuate the listening key 5 to connect the operator's telephone set with the 80 talking conductors so that the operators may converse, listening key 42 at the toll operator's position having previously been actuated to connect the toll operator's telephone set in circuit after the extinguishment of the 85 lamp 33 which is a signal to the toll operator that the manual operator has answered. After receiving the proper instructions as to the line with which connection is desired, the operators may restore the listening keys to normal position and the operator at the manual exchange may, in any well-known manner, establish connection with the 90 desired line.

95 After such a connection has been established as described in the preceding paragraph, the toll operator may desire to recall the operator at the manual exchange and this may be done by repeatedly and momentarily withdrawing the plug 35 from the 100 jack 36. Upon each withdrawal of this plug, relay 16 deenergizes to close its normal contact which establishes a short circuit for the high resistance right-hand winding of relay 11. The resistance of the circuit including the lamp 30 is thereby reduced to such an extent that the lamp is lighted. Upon each insertion of the plug 35 into the jack 36, however, relay 16 reenergizes to remove the short circuit of the high resistance right-hand winding of relay 11 so that the lamp is extinguished. Therefore, only during 105 each withdrawal of the plug is the lamp 30 lighted. In this manner, the lamp is lighted intermittently during such continued withdrawals of the plug and furnishes a signal to the operator at the manual exchange that the toll operator is recalling. After repeatedly removing the plug in this manner the toll operator may let the plug rest in the 110 jack and, of course, the relay 16 will remain energized. Since cutoff relay 34 is slow in releasing, impulse response relay 17 is not affected by such continued withdrawal of the plug 35. The operator at the manual 115 exchange, upon observing the flashing or intermittent lighting of the lamp 30, may actuate the listening key 5 to connect the telephone set in circuit with that of the toll operator which has been previously con- 120 125 130

nnected with the talking conductors through the actuation of the listening key 42. Instead of repeatedly withdrawing the plug from the jack to recall the operator at the 5 manual switchboard, the operator at the toll switchboard may repeatedly actuate the ringing key 37. Due to the noninductive shunt 28 connected around the winding of relay 16, this relay will not be sufficiently 10 energized by ringing current to maintain its armature attracted. Therefore the supervisory lamp of the connected cord circuit at the manual switchboard will be flashed in the same manner as before described.

15 What is claimed is:

1. In a telephone exchange system, in combination, a trunk circuit comprising a pair of talking conductors, inductive means 20 electrically dividing the talking conductors into inner and outer sections, a bridge for the outer section, an impulse sending device, an impulse response relay, a link circuit, a primary relay energized over one of the talking conductors of the inner section 25 upon the connection of the link circuit with the trunk circuit, a secondary relay for intermittently opening the bridge to control the impulse response relay, and an energizing circuit for the secondary relay controlled 30 by the impulse sending device and the primary relay.

2. In a telephone exchange system, in combination, a trunk circuit comprising a pair of talking conductors, inductive means 35 electrically dividing the talking conductors into inner and outer sections, a bridge for the outer section, an impulse sending device, an impulse response relay, a link circuit connected with the trunk circuit, means 40 for connecting the impulse sending device with the link circuit, a primary relay energized over one of the engaged talking conductors of the link circuit and inner section, and a secondary relay controlled over the 45 other engaged talking conductor of the link circuit and inner section by the impulse sending device and the primary relay for intermittently opening the bridge to control the impulse response relay.

50 3. In a telephone exchange system, in combination, a trunk circuit comprising a pair of talking conductors, inductive means 55 electrically dividing the talking conductors into inner and outer sections, a bridge for the outer section, an impulse sending device, an impulse response relay, means for connecting the impulse sending device with the trunk circuit, a primary relay energized over one of the talking conductors of the inner 60 section, a secondary relay controlled over the other talking conductor of the inner section by the impulse sending device and the primary relay for intermittently opening the bridge to control the impulse 65 response relay, an impedance element, and

means responsive to the disconnection of the impulse sending device from the trunk circuit for including the impedance element in the bridge.

4. In a telephone exchange system, in combination, a trunk circuit comprising a pair of talking conductors, inductive means 70 electrically dividing the talking conductors into inner and outer sections, a bridge for the outer section, an impulse sending device, an impulse response relay, means for connecting the impulse sending device with the trunk circuit, a primary relay energized over one of the talking conductors of the inner section, a secondary relay controlled 75 over the other engaged talking conductor of the inner section by the impulse sending device and the primary relay for intermittently opening the bridge to control the impulse response relay, and means responsive to the disconnection of the impulse sending device from the trunk circuit for disconnecting the secondary relay from the talking conductors.

5. In a telephone exchange system, in combination, a trunk circuit comprising a pair of talking conductors, inductive means 80 electrically dividing the talking conductors into inner and outer sections, a bridge for the outer section, an impulse sending device, an impulse response relay, means for connecting the impulse sending device with the trunk circuit, a primary relay energized over one of the talking conductors of the inner section, a secondary relay controlled 85 over the other engaged talking conductor of the inner section by the impulse sending device and the primary relay for intermittently opening the bridge to control the impulse response relay, and means responsive to the disconnection of the impulse sending device from the trunk circuit for disconnecting the secondary relay from the talking conductors.

6. In a telephone exchange system, in combination, a trunk circuit comprising a pair of talking conductors, inductive means 90 electrically dividing the talking conductors into inner and outer sections, a bridge for the outer section, an impulse sending device, an impulse response relay, means for connecting the impulse sending device with the trunk circuit, a primary relay energized over one of the talking conductors of the inner section, a secondary relay controlled 95 over the other engaged talking conductor of the inner section by the impulse sending device and the primary relay for intermittently opening the bridge to control the impulse response relay, and means responsive to the disconnection of the impulse sending device from the trunk circuit for disconnecting the primary relay from the talking conductors.

7. In a telephone exchange system, in com-

5 combination, a trunk circuit comprising a pair of talking conductors, inductive means electrically dividing the talking conductors into inner and outer sections, a bridge for the outer section, an impulse sending device, an impulse response relay, means for connecting the impulse sending device with the trunk circuit, a primary relay energized over one of the talking conductors of the inner 10 section, a secondary relay controlled over the other talking conductor of the inner section by the impulse sending device and the primary relay for intermittently opening the bridge to control the impulse response relay, an impedance element, and means responsive to the disconnection of the impulse sending device from the trunk circuit for including the impedance element in the bridge and for disconnecting the primary and secondary relays from the talking 15 conductors.

8. In a telephone exchange system, in combination, a trunk circuit comprising a pair of talking conductors, inductive means electrically dividing the talking conductors into inner and outer sections, a bridge for the outer section, an impulse sending device, an impulse response relay, means for connecting the impulse sending device with the trunk circuit, a primary relay energized over one of the talking conductors of the inner section, a secondary relay controlled over the other talking conductor of the inner section by the impulse sending device and the primary relay for intermittently opening the bridge to control the impulse response relay, a relay in the bridge controlled over the outer section of the trunk circuit, and a relay controlled by the bridge relay and responsive to the disconnection of the impulse sending device from the trunk circuit for disconnecting the primary and secondary relays from the talking conductors.

9. In a telephone exchange system, in combination, a trunk circuit comprising a pair

of talking conductors, inductive means electrically dividing the talking conductors into inner and outer sections, a bridge for the outer section, an impulse sending device, an impulse response relay, means for connecting the impulse sending device with the trunk circuit, a primary relay energized over one of the talking conductors of the inner section, a secondary relay controlled over the other talking conductor of the inner section by the impulse sending device and the primary relay for intermittently opening the bridge to control the impulse response relay, and a relay responsive to the disconnection of the impulse sending device from the trunk circuit for disconnecting the primary and secondary relays from the talking conductors and for maintaining these relays in energized condition.

10. In a telephone exchange system, in combination, a trunk circuit comprising a pair of talking conductors, inductive means electrically dividing the talking conductors into inner and outer sections, said inner section having a normally open contact in said talking conductors, a bridge for the outer section, an impulse sending device, an impulse responsive relay, means for connecting the impulse sending device with the trunk circuit, a primary relay energized over one of the talking conductors of the inner section, a secondary relay controlled over the other talking conductor of the inner section by the impulse sending device and the primary relay for intermittently opening the bridge to control the impulse response relay, and a relay responsive to the disconnection of the impulse sending device from the trunk circuit for disconnecting the primary and secondary relays from the talking conductors and for closing the normally open contact.

In witness whereof, I hereunto subscribe my name this 3rd day of October A. D., 1919.

CHARLES W. KECKLER.
